CLAIM

The ornamental design for an electric vehicle charger, as shown and described.

DESCRIPTION

The patent or application file contains at least one drawing executed in color. Copies of this patent or patent application publication with color drawing(s) will be provided by the Office upon request and payment of the necessary fee.

1. Electric vehicle charger

1.1 : Front

1.2 : Back

1.3 : Right

1.4 : Bottom

1.5 : Top

1.6 : Perspective

Electric vehicle charger is used to charge electric transportation means including electric vehicles; the left view, which is symmetrically identical with the right view, is omitted; the color deviations in the views are due to shadow or light reflections.

The faded or grayed out portions surrounded by broken lines indicate portions of the article that form no part of the claimed design. The broken lines directly adjacent to the faded or grayed out portions illustrate boundaries that form no part of the claimed design.
